UNITED STATES PATENT OFFICE.

CHARLES B. SANDERS, OF MONTCLAIR, NEW JERSEY, ASSIGNOR TO THE UNION BAG & PAPER COMPANY, OF NEW YORK, N. Y., A CORPORATION OF NEW JERSEY.

WEB-CUTTING MECHANISM FOR ENVELOP-MACHINES AND SIMILAR MACHINES.

1,169,197.

Specification of Letters Patent.

Patented Jan. 25, 1916.

Application filed May 14, 1914. Serial No. 838,596.

To all whom it may concern:

Be it known that I, CHARLES B. SANDERS, a citizen of the United States, and resident of Montclair, in the county of Essex and State 5 of New Jersey, have invented certain new and useful Improvements in Web-Cutting Mechanism for Envelop-Machines and Similar Machines, of which the following is a specification.

10 This invention relates to web cutting mechanism of envelop machines or similar machines for continuously moving webs, and has for its object to provide means by which the cut or printed impression may be produced at differently spaced intervals in the web without alteration of the printing or cutting roll.

20 A further object of my invention is to provide a mechanism of this character which may be combined with an envelop machine to produce envelops of different lengths in one machine with simple changes in adjustment.

25 Further objects of the invention reside in improvements in the various details of construction of the mechanism as will be herein-after described and pointed out in the appended claims.

30 In the accompanying drawings I have illustrated a preferred embodiment of my invention as combined with an envelop machine and in the said drawings: Figure 1 is a plan view of my improved machine; Fig. 2 is a longitudinal section of the same; Fig. 3 is a side view of a portion of the 35 machine showing the driving gears; Figs. 4, 5, 6 and 7 are detailed views of the cutter adjusting mechanism; Figs. 8 and 9 are diagrammatic views showing the envelop in its various stages of manufacture; Fig. 10 is a 40 partial plan view of a modified machine showing a printing as well as a cutting mechanism.

45 Referring now to the drawings 1 indicates the frame of the machine at one end of which is supported a roll of paper 2 from which envelops are to be made. The paper from the roll passes around through the guide-rollers 3, and thence between the pasting 50 disk 4 and coöperating roller 5. The pasting disk 4 runs in a paste tank 6 which is supported on the machine frame and applies a line of paste on one edge of the web as it is continuously fed into the machine.

After passing beyond the roller 5 the web 55 passes between the edge cutting rolls 7 and 8, of which the bottom roll 8 consists of a hardened steel cylinder, against which the knives on the roll 7 work in cutting the web. As shown more particularly in Fig. 1 the 60 knives carried by the roll 7 comprise two slightly inclined but substantially longitudinal knives 9, forming with the V-shaped circumferential knife 10 a cutting die, cutting each edge of the paper the shape shown 65 at *a* in Fig. 8.

Beyond the rolls 7 and 8 the web runs between the coöperating creasing rolls 11 and 12 which crease the web along the line *b* to form the side flaps *c* and *d*. The web 70 then passes through the side folders 13 by means of which the flaps *c* and *d* are laid one over the other to form the body of the envelop. This folding mechanism I have not shown in detail as it may be of the kind 75 known as "plowshare" folders, and forms no part of the present invention. The folding mechanism comprises plates properly shaped to lay or fold over the flap as the web passes beneath them. Beyond the side folders are 80 arranged draw rolls 14 and 15 by which the web of paper is drawn through the machine, these rolls being made of any suitable construction to secure a sufficient grip upon the paper. As shown the bottom roller 15 85 comprises a metal shell, while the upper roller consists of two disks whose peripheries are designed to grip the surface of the lower roll.

The end of the web as it leaves the draw- 90 ing rolls is thrust between the cut off rolls 16 and 17 by means of which the blanks are separated from the web along the line *e* as shown in Fig. 9. These rolls comprise a lower hardened steel roller and upper 95 roller carrying a knife of proper shape to give the desired cut. Beyond the cutting rolls are arranged the bottom forming rolls which I will later describe.

The shaft 18^a of the lower cutting roll 17 100 constitutes the driving shaft of the machine and is extended beyond the machine frame to receive the fast and loose pulleys 18. The upper roll 16 is driven by means of a pinion 19 between the frame 1 and the bearing 105 of the roll.

Attached to the shaft 18^a beyond the frame is a pinion 32 which drives through the gear

33, the pinion 34 on the shaft of the lower draw roll 15. As shown in Fig. 3 the gear 33 is supported on a stub axle mounted for adjustment on an arc concentric with the shaft 5 of the lower draw roll whereby by substituting pinions of different sizes for the pinion 32 the speed of the draw rolls relative to the driving shaft may be varied and consequently the speed of movement of the web 10 increased or decreased as desired. The purpose of this adjustment is to secure envelopes of different lengths. The length of the envelop is obviously determined by the distance between the edge cuts effected by the rolls 7 and 8, and this distance is determined by the amount of paper fed for each revolution of the cutting rolls. It is obvious however that at the moment of cutting the surface speed of the cutting rolls at their point 15 of engagement must be equal to the speed of the web, otherwise when the paper is gripped between the knives and the lower roll, the pull of the paper by the more rapidly revolving draw rolls would tear the paper and 20 cause an imperfect envelop. In order therefore to vary the length of the envelop by varying the speed movement of the web I have provided means for driving the cutting rolls in such a manner that the time required 25 for a complete revolution remains the same, but the surface speed of the periphery of the rolls 7 and 8 during the moment of cutting may be varied in synchronism with the various speeds of the drawing rolls.

30 The cutting rolls are driven from the driving shaft by means of a pinion 20 which drives through the idler 21, the gear 22 from which the edge cutting rolls are driven as will now be described. Extending beneath 35 the folder 13 is a transverse bar of the frame 1, on which is mounted a shaft 23 which may be rotatably adjusted by means of a hand wheel 24 and locked in its adjusted position by means of its split clamping bearings 25 as 40 shown in Figs. 4 and 5. The shaft 23 is provided beyond its bearing with a crank pin 26 which forms a bearing for the gear 22. On its face away from the shaft 23 the gear 22 is provided with a roller 27 eccentrically disposed with relation to the gear and operating in a diametric groove 28 across the face of a disk 29 attached to a shaft 30 mounted in fixed bearings on the machine frame. The shaft 30 is in the same horizontal plane as 45 the shaft 23 but is out of alinement therewith a distance equal to the eccentricity of the crank pin 26 whereby the crank pin may be adjusted from the position of alinement with the shaft 30 to a position eccentric 50 thereto to an extent equal to twice its eccentricity relative to the shaft 23. From the shaft 30 the edge cutting rolls 7 and 8 are driven by means of a longitudinal shaft 31 and suitable mitered gearing.

55 It is obvious that when the crank pin 26 is

concentric with the shaft 30 the roller 27 and grooves 28 will act as a shaft coupling and drive the shaft 30 at the same speed as the gear 22. When the crank pin 26 is eccentric to the shaft 30, the shaft 30 will still make 60 one revolution for each revolution of the gear 22, but during that portion of the revolution in which the point of engagement of the roller 27 and the groove 28 is most distant from the center of the shaft 30, the speed of 65 the shaft 30 will be slower than that of the gear in the ratio of the distances of the roller 27 from the center of the shaft and the center of the crank pin respectively. When the roller is at the point in its revolution opposite the point shown in Fig. 4, the speed of the shaft 30 will be greater than 70 that of the gear in the same ratio. By arranging the intermediate gearing of the cutting rolls so that the cutting takes place substantially at the instant in the rotation of the shaft 30 that its speed is greatest, the speed during the cutting can be adjusted by 75 the hand wheel 24 to substantially synchronize with the speed of the web as varied by 80 the change in gear 32. To permit the gear 22 to be adjusted as described, and to retain the driving connection with the gear 20 the idler 21 is supported on a stub bearing 21* 85 mounted for adjustment in the machine frame on an arc concentric with the gear 20. The bottom forming mechanism forms no 90 part of the invention of the present application and therefore has not been shown in detail and comprises briefly a pair of creasing rolls 35, 36 which creases a blank along the line f of Fig. 9, and delivers it to the folding and pasting rolls 37, 38, which grip 95 the blank along the line of the end fold, pasting the flap against the body of the blank to form the completed envelop as 100 shown at E in Fig. 9. The envelop is delivered from the rolls 37, 38 by means of a stripper 39 through which the envelop is 105 guided to the delivery belt 40.

110 The feed roller 5 is preferably driven with the draw rolls 14, 15 to have the same surface speed as the paper. As shown this roll is driven through a side shaft 41 having a miter gear on each end meshing with miter gears on the end of the lower draw roll shaft and the shaft of the roll 5 respectively. The creasing rolls 11, 12 are 115 also driven from the shaft 41, by means of suitable miter gears 42, the shafts of the rolls being connected by spur gears one of 120 which is indicated at 43. For convenience in determining the proper adjustment of the cutting mechanism the hand wheel 24 is provided with a scale on its periphery 125 with which cooperates the index pointer 45 attached to the adjacent bearings of the shaft 23. The scale may be marked with numbers indicating the length of the envelop to be formed, which numbers will 130

also be stamped on the various gears 32 so that the two adjustments may be accurately obtained when changing the length of the envelop without experiment.

5. It will be obvious that my improved mechanism may be employed with equal advantage for operating a printing mechanism either in combination with the cutting mechanism or alone to print at differently spaced intervals along a continuous web. In Fig. 10 I have shown a plan view of the envelop machine embodying my improved cutting mechanism, and also a printing mechanism for printing a return address or other legend upon each envelop. As here shown the machine is the same as in Figs. 1 and 2 except that the frame is the same in Figs. 1 and 2 except that the frame is elongated between the pasting roll 5 and the cutting rolls 7 and 8 to provide space for the pair of printing rolls 50 and 51. It will be understood that the upper roll constitutes the platen and the lower roll carries the type, not shown. The shafts of the printing rolls are geared together at 54 and the shaft of the lower roll is extended beyond the frame and provided with a miter gear driven from a similar gear attached to the shaft 31 whereby the printing rolls and cutting rolls will be driven and adjusted in synchronism.

I have described my invention in detail in order that it may be fully understood, but my invention is of course not limited to such details of construction, and, covers all such modifications of the same as fall within the scope of the appended claims. It will also be understood that the invention is not limited to an envelop machine, but as stated above, may be employed with equal advantage in any machine embodying a web cutting or printing mechanism.

Having thus described my invention, what I claim and desire to secure by Letters Patent is:—

45. 1. In a machine of the class described, the combination of a pair of rollers for feeding the web, means for continuously driving said rollers at various speeds, a pair of

rollers carrying devices adapted to engage and operate upon said web at intervals in 50 the rotation of said rollers, and means for driving said last mentioned rollers comprising a variable speed gearing whereby the surface speed of said rollers during the interval of their engagement may be varied 55 without varying the time of rotation of said rollers, said means comprising a rotatable crank, a disk driven thereby, and means for varying the relative positions of the centers of rotation of said crank and said disk. 60

2. In a mechanism of the class described, the combination of a pair of coöoperating rolls, a pair of draw rolls for feeding the web between said first mentioned rolls, means for driving said first mentioned rolls 65 comprising a driving member having a crank pin, a driven disk having a transverse slot engaged by said crank pin, and means for bodily adjusting the shaft of said driving member relative to the center of rotation of said driven disk. 70

3. In a machine of the class described, the combination of a pair of rolls, a pair of draw rolls for feeding a web through said first mentioned rolls, a driving shaft, a 75 change gear between said driving shaft and said draw rolls, means for driving said first mentioned rolls comprising a supporting shaft having a stub axle eccentric thereto, a driving gear supported on said stub axle and 80 driven from said driving shaft, a driven shaft out of alinement with said supporting shaft, a disk mounted on said driven shaft and having a transverse slot, a crank pin carried by said driving gear and engaging 85 said slot, driving connections between said disk and said rolls, and means for rotatably adjusting said supporting shaft and locking the same in adjusted position.

Signed at Montclair, in the county of 90 Essex and State of New Jersey, this 9th day of May, 1914.

CHARLES B. SANDERS.
